UNITED STATES PATENT OFFICE.

GEORGE I. WORLEY, OF KANSAS CITY, MISSOURI, ASSIGNOR OF ONE-HALF TO
CHARLES F. DEHNER, OF KANSAS CITY, MISSOURI.

ROAD-OILING VEHICLE.

1,093,818.

Specification of Letters Patent. Patented Apr. 21, 1914.

Application filed April 1, 1913. Serial No. 758,265.

To all whom it may concern:

Be it known that I, GEORGE I. WORLEY, a citizen of the United States, residing at Kansas City, in the county of Jackson and State of Missouri, have invented certain new and useful Improvements in Road-Oiling Vehicles, of which the following is a specification.

This invention relates to road oiling vehicles and the special object in view is to produce a device of this character in which the oil to be applied to the roads will be spread upon the surface treated in the form of a fine mist.

Another object is to provide an oil carrying tank with means for confining the air therein under pressure to force the oil out and with suitable connections between the air supply and the oil discharging nozzles for atomizing the oil.

With these and other objects in view the invention comprises certain novel and peculiar features of construction as herein-after described and claimed, and in order that the same may be fully understood reference is to be had to the accompanying drawings, in which—

Figure 1, is a side elevation of a road oiling vehicle embodying my invention; Fig. 2, is a rear view in elevation of certain connections at one of the rear corners of the vehicle; Fig. 3, is a plan view of the vehicle partly broken away to show the pipes and their connections; Fig. 4, is a sectional detail of one of the adjustable rod and lever connections; Fig. 5, is a vertical section through one of the oil atomizing nozzles with its pipe connections and regulating valves, and Fig. 6, is a horizontal section 40 through the lower end of said nozzle on the line VI—VI of Fig. 5.

Referring to the drawings, 2 represents the bed of a vehicle of any desired type and which may be driven in any suitable manner. Upon the bed 2 is carried an oil supply tank 4 adjacent one end of which I also mount upon the bed 2, an engine or motor 6 of any suitable type for driving an air compressor 8. The air compressor is also carried by the bed 2 and supplies compressed air to the tank 4 through a pipe 10 leading into the top of said tank and fitted with a pressure gage 12.

Communicating with the air space in the top of the tank 4 is an air dome 14 to pro-

tect the opening of the outlet pipe 16 from the splashing of the oil in the tank when the vehicle is moving. The pipe 16 leads to the rear of the vehicle and down past the rear end of the bed 2, where it communicates with three branch pipes 18, two of which run toward the sides of the vehicle, the third running forward beneath the vehicle bed 2, each branch pipe being for the purpose of supplying air to one of a series of nozzles 20.

For supplying oil to the nozzles 20, a pipe 22 having a valve 24 is connected with the bottom of the tank 4 and leads into the nozzle at the opposite side from the branch air pipe 18. Each nozzle 20 has a cross-shaped body portion 26, as shown in Fig. 5, having horizontal passages 28 and 29 therein for communicating with the pipes 18 and 22, the said passages being separated at their inner ends by a partition 30. The connection with the said pipes is made by means of collars 31, swiveled on the ends of the pipes and engaging suitable threaded terminals formed at the ends of passages 28 and 29 whereby it will be understood that the nozzle is adapted to assume different angular positions aside from the vertical position shown. Communicating with the inner ends of the passages 28 and 29 and extending downward therefrom toward the nozzle opening, are parallel passages 32, the lower ends of which are sealed by plugs 33 which are adapted to be removed for the purpose of cleaning the nozzle. The openings into the upper ends of the passages 32 are reduced and the amount of opening regulated by means of screw rods 34, the lower ends of which are tapered and adapted to be seated into said reduced ends of passages 32 and close the same or to be raised by turning the rods to lift said tapered ends and increase the size of the opening. The threaded portions of the rods 34 operate in the upper section of the body portion 26 of the nozzle, the upper ends of the openings for the rods being sealed by packing rings 36 upon which rests a collar 38 having openings for the rods, and held tightly in place by a cap 40, engaging the exterior of the portion 26 which is properly threaded for said cap. Threaded upon the lower end of the body portion 26 is an acorn-shaped nozzle piece 42, having a slit opening 44, the upper edge of the nozzle piece abutting against a collar 46 upon the body portion 26.

To establish communication between the passages 32 and the interior of the nozzle piece 42, openings 48 are formed through the body portion 26, at the lower ends of 5 said passages 32, said openings being formed through the outside wall of the portion 26 at an angle to the radius of said body portion instead of directly through the wall, the object of this being to direct the 10 oil and air out through the openings at an angle approaching a tangent to the inner curved surface of the nozzle piece. By this construction a vigorous whirling action of the air and oil is set up within the nozzle 15 piece in consequence of which the oil is thoroughly atomized and forced out through the opening 44 in the form of a fine mist.

It is necessary to have connections from the front of the vehicle whereby the flow of 20 air and oil through the nozzles may be regulated by the driver, and I arrange this as follows:—For turning the rods 34, each rod has secured to its upper end, a crank arm 50, each pair of arms 50 extending in the same 25 general direction and having pivoted thereto a pair of rods 52, the opposite ends of which rods are clamped in a cross bar 54 so that the rods 52 of each pair will move in unison as its cross bar 54 moves. The rods 30 52 are adjustably connected to said cross bars and held clamped therein by set screws 56. To the middle of each cross bar is connected a rod 58, having a reduced end for engagement with the cross bar and secured 35 thereto by a nut 60 so that endwise movement of the rod 58 in either direction will correspondingly move the bar 54. Each rod 58 is joined at its opposite end to one arm of a bell crank lever 62, a series of three 40 of which are pivotally mounted upon a bracket 64 secured to the vehicle body 2. The other arms of said levers 62 are joined by links 66 to the adjacent arms of the bell cranks 68 pivoted upon a bracket 70 carried 45 by the body 2, and the other arms of said bell cranks 68 are connected by links 72 to arms 74 secured to the lower ends of a series of sleeves of different diameters journaled together within the bracket 76 secured to 50 the front end of the bed 2, and operated by a series of crank arms 78 provided with hand grips 80. It will thus be seen that by manipulation of the proper lever 78 any one of the three sets of rods 34 will be turned 55 to regulate the corresponding nozzle and the position of the rods will remain as set without any securing means for the crank arms, due to a certain amount of friction between the rods and their bearings.

60 From the foregoing it will be seen that I have produced a road oiling vehicle embodying the features of advantage enumerated as desirable in the statement of the object of the invention, and while the above represents one embodiment of the same I do 65

not wish to be limited to the precise construction and arrangement shown but reserve the right to such changes and modifications as fall within the spirit and scope of the appended claims.

I claim:—

1. A road oiling vehicle comprising an air tight oil tank provided with a wheeled support, compressed-air-supplying means also mounted on said support in communication with the space over the oil in said oil tank, a series of compound oil and air discharge nozzles each communicating with both the oil and the air in said tank whereby the oil is forced out of the tank by air pressure and atomized as it is discharged from said nozzles, and connections between said nozzles and the front of the vehicle whereby the nozzles may be controlled each independently of the others. 70

2. A road oiling vehicle, comprising an oil tank and supporting means therefor, a discharge pipe connected to the tank, a series of compound air and oil discharge nozzles connected with said pipe, means for supplying compressed air to said nozzles, and a connection between each nozzle and the front of the vehicle whereby the nozzles may be controlled each independently of the others. 85

3. A road oiling vehicle, comprising an oil tank and supporting means therefor, a discharge pipe connected to the tank, a series of compound air and oil discharge nozzles connected with said pipe, means for supplying compressed air to said nozzles, each nozzle being provided with an air valve and an oil valve, and independent connections between each nozzle and the front of the vehicle whereby the valves of each nozzle 100 may be controlled simultaneously. 95

4. A road oiling vehicle comprising an oil tank and supporting means therefor, an oil discharge pipe connected to the tank, a compressed-air supply pipe, the delivery ends of said pipes approaching each other in a line extending longitudinally of the vehicle, a compound air and oil discharge nozzle swiveled at one side to one of said pipes and at its other side to the other pipe, 110 thereby permitting said nozzle to be swung laterally into different positions about a longitudinally extending horizontal axis, said nozzle being provided with an air valve and an oil valve, and connections from the front 115 of the vehicle whereby the valves of said nozzle may be controlled simultaneously. 120

5. A road oiling vehicle comprising an oil tank and supporting means therefor, an oil discharge pipe connected to the tank, a compressed-air supply pipe, each of said pipes having a branch extending to each of the rear corners of the vehicle, the delivery ends of the branches at each of said corners approaching each other in a line ex- 125 130

tending longitudinally of the vehicle, a compound air and oil discharge nozzle at each of said corners, each nozzle being swiveled between one set of delivery ends, thereby 5 permitting it to be swung laterally into different positions about an axis extending longitudinally of the vehicle, and a connection between each nozzle and the front of the vehicle whereby the nozzles may be controlled 10 each independently of the other.

6. A road oiling vehicle, comprising an air tight oil tank and supporting means therefor, an oil discharge pipe connected to the tank, a series of compound oil and air discharge nozzles connected to said pipe, a compressed air pipe connected to said nozzles and to the space over the surface of the oil in said tank, each of said nozzles having an air valve and an oil valve, a crank 15 arm fitted to the stem of each valve, rods connected to said crank arms, a cross bar adjustably clamped to the ends of each pair of said connecting rods, and means for independently reciprocating each cross bar from 20 the front of the vehicle.

25 7. A road oiling vehicle provided with a

plurality of compound oil and air discharge nozzles pivotally mounted about axes extending longitudinally of the vehicle, means for supplying both oil and compressed air 30 to all said nozzles, and independent connections between each of said nozzles and the front of the vehicle whereby the flow of oil and air through any one nozzle may be 35 simultaneously controlled.

8. A road oiling vehicle provided with a plurality of compound oil and air discharge nozzles pivotally mounted about axes extending longitudinally of the vehicle, means for supplying both oil and compressed air 40 to all said nozzles, and an independent operating connection leading to each of said nozzles whereby the flow of oil and air through any one nozzle may be simultaneously controlled. 45

In testimony whereof, I affix my signature, in the presence of two witnesses.

GEORGE I. WORLEY.
